BOILER CLEANER

Norman L. Snow, New Canaan, Conn., and Willis P. Thomas, Detroit, Mich., assignors to Diamond Power Specialty Corporation, Detroit, Mich., a corporation of Michigan

Application January 24, 1930, Serial No. 423,140

14 Claims. (Cl. 122—392)

This invention relates to boiler cleaners and has particular reference to a boiler cleaner adapted to discharge cleaning fluid adjacent the portions of the boiler to be cleaned.

5 One object of this invention is to provide a boiler cleaner of the above mentioned character which will include a blower element having a plurality of discharge openings and means associated with this blower element for controlling the flow 10 of cleaning fluid through said openings according to a predetermined desired sequence.

15 A further object of this invention is to provide a boiler cleaner of the above mentioned character which will include a blower element having means for effecting a circulation of a cooling fluid through the blower element during the periods when the blower element is not operating to discharge jets of cleaning fluid adjacent the portions of the boiler to be cleaned.

20 Other objects and advantages of this invention, together with the numerous novel details of construction thereof, will become more apparent as the following description proceeds, particularly when reference is had to the accompanying drawings wherein

25 Figure 1 is a sectional view through a boiler showing a blower element constructed in accordance with the teachings of this invention, mounted in the same.

30 Figure 2 is a sectional view taken substantially on the line 2—2 of Figure 1.

35 Figure 3 is a horizontal sectional view taken through a portion of the blower element shown in Figure 1.

40 Figure 4 is a vertical sectional view through a head adapted to be associated with the blower element shown in Figure 1.

45 Fig. 4A is an enlarged sectional view of a portion of the structure shown in Fig. 4.

50 Figure 5 is a fragmentary sectional view through a slightly modified form of valve actuating mechanism adapted to be substituted for a portion of the structure shown in Figure 4.

55 Figure 6 is a longitudinal sectional view through a slightly modified form of blower element.

Figure 7 is a fragmentary view similar to Figure 6 showing a still further form which the blower element may assume.

50 Figure 8 is a semi-diagrammatic sectional view through a boiler showing a blower element formed as shown in Figure 7 mounted in the same.

55 Figure 9 is a fragmentary sectional view through a blower element showing a slightly modified form of valve mounted in the same.

Figure 10 is a sectional view taken on the line 10—10 of Figure 9.

Figure 11 is a view similar to Figure 9 showing a still further form which the valve may assume.

Figure 12 is a sectional view taken on the line 5 12—12 of Figure 11.

Figure 13 is a view similar to Figure 9 showing a still further form of valve.

Figure 14 is a horizontal sectional view taken substantially on the line 14—14 of Figure 13, and 10

Figure 15 is a sectional view taken substantially on the line 15—15 of Figure 13.

Referring then particularly to the drawings wherein like reference characters designate corresponding parts throughout all views, there is 15 shown in Figure 1 a boiler designated generally by the reference character 20, this boiler including a boiler wall 21 provided with an opening 22. A blower element 23 projects through this opening and is provided with a plurality of discharge 20 openings 24 for directing jets of cleaning fluid adjacent the portions of the boiler to be cleaned, such for example as the tubes 25.

Heretofore it has been customary to supply 25 cleaning fluid to a blower element of this character and to permit this cleaning fluid to be simultaneously discharged from all of the discharge openings thereof whereby cleaning fluid is discharged from the blower element in the form of a plurality of spaced jets. In operating a blower

30 element in this manner, none of the jets are particularly powerful in view of the fact that the supply of cleaning fluid to the blower element is limited by the size of the supply pipe and of the blower element and this limited supply must be 35 distributed between all of the jets which are discharging at the same time. The present invention

40 contemplates the elimination of this objection by providing means for closing the discharge openings 24 to prevent the discharge of cleaning fluid through these openings, the arrangement being such that one discharge opening is uncovered at a time whereby all of the cleaning fluid in the blower element is discharged in the form of a single powerful jet rather than in the form of a plurality of less powerful jets. Thus the openings 24 may be successively uncovered according to a predetermined desired sequence so that 45 cleaning fluid may be discharged from the blower element in the form of a single powerful jet from any one of a plurality of spaced points throughout the length of the blower element.

50 To accomplish the above results there is provided a valve strip 26 arranged longitudinally within the blower element, this valve strip being 55

- arcuate in cross section to snugly engage the inner periphery of the blower element, as clearly shown in Figure 2 of the drawings. The valve strip 26 is preferably flexible and is therefore held against the inner periphery of the blower element adjacent the discharge openings therein by the pressure of the cleaning fluid when cleaning fluid is supplied to the blower element. For holding the valve strip in position when the supply of cleaning fluid to the blower element is cut off, pins 27 are preferably provided, these pins extending transversely of the blower element at spaced points and forming bearings for the valve strip.
- As clearly illustrated in Figure 3 of the drawings, the valve strip is preferably provided throughout its length with a plurality of openings 28 adapted upon longitudinal movement of the valve strip to successively register with the discharge openings 24. The arrangement is such that the openings 24 will be uncovered in accordance with a predetermined desired sequence so that the jets of cleaning fluid will be discharged from predetermined spaced points throughout the length of the blower element according to a desired order. As illustrated, the openings 24 may be equally spaced throughout the length of the blower element, while the openings 28 may also be equally spaced throughout the length of the valve strip, the openings 28, however, being spaced closer to each other than are the openings 24.
- Thus, as illustrated in Figure 3 of the drawings, when the openings are arranged in this manner, at any given position of the valve strip, one of the openings 28^a therein will be spaced one step from one of the openings 24^a, while the next opening 28^b of the valve strip will be spaced two steps from the opening 24^b of the blower element. The remaining openings in the valve strip will be spaced 3—4, etc., steps from their respective openings in the blower element, as will be readily apparent. Thus upon movement of the valve strip to the left, as viewed in Figure 3, opening 28^a will first register with port 24^a, while opening 28^b will be moved one step closer to opening 24^b, the remaining openings in the valve strip being in each case moved one step toward or away from their coacting openings in the blower element. Thus upon a second movement of the valve strip, opening 28^a will be moved one step beyond opening 24^a, while opening 28^b will be moved to registration with opening 24^b. The openings 24 in the blower element will thus be uncovered successively throughout the length of the blower element to permit cleaning fluid to be discharged from the blower element from successive points throughout the length thereof.
- The blower element 23 may be stationary with in the boiler, or if desired, this blower element may be mounted for rotation or for oscillation in a manner which will hereinafter be more fully brought out. There is also provided a rod 29 welded or otherwise secured as at 30 to the end of the valve strip and projecting to a point exteriorly of the boiler wall to provide means for effecting a longitudinal movement of the valve strip and a registration of the ports therein with the ports in the blower element as above brought out.
- In Figure 4 there is disclosed one type of head which may be associated with the blower element above described for supplying cleaning fluid to this blower element and for effecting a rotation or oscillation thereof. This head is designated generally by the reference character 35 and includes a goose-neck 36 connected to a cleaning fluid supply pipe 37. A swivel tube 38 is coupled to the blower element and is journaled as at 39 within the upper end of the goose-neck.
- Fixed as at 40 to the goose-neck, is a bracket 41 which at its upper end is tied by a rod 42 to a bracket 43 formed on the upper end of the goose-neck. A sheave wheel 44 is rotatably mounted on this tie rod and is adapted to be rotated by a suitable chain 45 in accordance with the usual practice. A pinion 46 fixed to rotate with the sheave wheel meshes with a gear 47 fixed to the swivel tube whereby rotation of the sheave wheel effects a rotation of the gear 47 and a rotation of the swivel tube and blower element. If desired, certain of the spaces between the teeth on the gear wheel 47 may be closed to form stops limiting rotation of the gear wheel to a predetermined arc, thus limiting rotation of the blower element to a predetermined arc and compelling oscillation of the same.
- For controlling the supply of cleaning fluid to the blower element there may be provided a valve 50 having a stem 51. A cam 52 fixed to the face of the gear 47 engages a trigger 53 pivoted on the goose-neck, this trigger being in turn connected to the valve stem 51 whereby the valve is periodically actuated upon rotation or oscillation of the blower element.
- For actuating the valve strip the rod 29 may be extended through the swivel tube and through a packed bearing 55 formed in the upper end of the goose-neck 36. Rotatably mounted on the projecting end of the rod 29 is a sleeve 56, this sleeve being held against longitudinal movement on this rod by the nuts 57 and 58 which engage its opposite ends. Supported in spaced relation to the end of the goose-neck as by the arms 59 is a bearing bracket 60 which supports a suitable shaft 61 on which is mounted a pinion 62 which engages teeth 63 formed on the upper face of sleeve 56. A hand wheel 64 fixed to the shaft 61 provides means for rotating this shaft and for effecting a longitudinal movement of the sleeve 56 and valve strip as will be readily apparent. If desired, suitable indicia (not shown) may be placed on the hub of the hand wheel and on the bearing bracket 60 to indicate sufficient rotation of the hand wheel 64 to effect a single step movement of the valve strip as above brought out.
- As mentioned before, it forms a feature of this invention to provide means for effecting a circulation of a cooling fluid through the blower element when the blower element is not operating to discharge jets of cleaning fluid. To accomplish this result, a port 70 is formed in the goose-neck 36 at a point above the valve 50. A ball 71 is held adjacent the port 70 by a suitable cage 72, the arrangement being such that when cleaning fluid is supplied to the goose-neck, the ball will be forced into engagement with the port to close the same. When, however, the supply of cleaning fluid to the goose-neck is cut off, the ball will fall by gravity away from the port 70 to permit air to enter this port, as will be readily apparent.
- When the blower element is not operating to discharge jets of cleaning fluid, the valve strip may be actuated to uncover the end nozzle of the blower element, that is, the nozzle most remote from the blower head, so that air which enters the goose-neck through port 70 will be compelled to flow entirely through the blower element before it escapes through the open dis-

charge opening of the blower element. In general, it will be found that the furnace draft will be sufficient to draw air through the blower element to cool the same, but if sufficient air is not drawn through the element by the furnace draft, a suitable blower of any desired character (not shown) may be mounted on the goose-neck adjacent the port 70 therein, to force air or any desired cooling fluid through the blower element 10 and out through the uncovered discharge opening thereof.

In Figure 5 a slightly modified form of actuating mechanism for the valve strip is disclosed. In this form of construction the rod 29^a projects through the packed bearing 55^a of the goose-neck 36^a as in the above described form of construction. Fixed to the projecting end of the rod is a sleeve 75 provided on its outer periphery with a plurality of spaced grooves 76. A handle 77 is provided for the end of the actuating rod, this handle being fixed to the sleeve 75 and to the actuating rod by a suitable cross pin 78. A spring 79 has its one end fixed at 80 to the goose-neck and has its other end arranged to engage the grooves 76 formed in the sleeve 75, as will be readily apparent. Engagement of the end of the spring in one of the grooves indicates that the valve strip is in a position to uncover one of the ports in the blower element, and the arrangement is such that engagement of the end of the spring in successive grooves will indicate successive uncovering of the ports in the blower element according to a predetermined desired sequence.

In Figure 6 a slightly modified form of blower element is disclosed, this element being designated by the reference character 85 and being provided with a valve strip 86 similar in all respects to the valve strip 26. In this form of construction, however, the discharge openings 87 of the blower element are fitted with nozzles 88 or 89, it being noted that the nozzles 88 are relatively long while the nozzles 89 are relatively short. Thus the character of the jets of cleaning fluid discharged from the blower element may be regulated, a long nozzle 88 being fixed to the blower element when it is desired to direct the jet of cleaning fluid a considerable distance from the blower element, and a short nozzle 89 being fixed to the blower element where a shorter jet of cleaning fluid is desired. In this case the nozzles will be successively placed in communication with the interior of the blower element by a proper actuation of the valve strip 86. The blower element may be associated with the head disclosed in Figure 4, thus being mounted for rotation or oscillation, or may be directly connected to the cleaning fluid supply pipe and thus be fixed against movement within the boiler.

In Figures 7 and 8 a further slightly modified form of construction is shown as including a blower element 90 similar to the blower element 85 and provided with a valve strip 91 similar to the valve strip 86. In this form of construction nozzles 92 are fixed in the discharge openings 93, these nozzles, however, being all relatively long, as clearly illustrated.

In Figure 8 the blower element shown in Figure 7 is shown in position in a boiler, designated generally by the reference character 94, and by reference to this figure it will be noted that this boiler is provided with a lower wall 95 which is provided in its upper end with a recess 96 in which the blower element is mounted. This blower element may be provided with a head

similar to that disclosed in Figure 4, there being provided stops for limiting movement of the blower element to compel an oscillation of the same. Thus when the blower element is not discharging jets of cleaning fluid, it may be rocked to the position shown in full lines in Figure 8, in which position the nozzles will be entirely housed within the recess 96 and thus shielded from the heat of the boiler. When it is desired to discharge cleaning fluid from the blower element, the blower element is rocked to move the nozzles up to the dotted line position, the cam associated with the head being so designed that cleaning fluid will be supplied to the blower element through a predetermined arc, as indicated at 97 in Figure 8. Thus the nozzles may be normally shielded from the heat of the boiler but may be moved out of the recess in which they are housed and rocked to a predetermined desired blowing arc.

In Figures 9 and 10 a slightly modified form of valve strip is shown for controlling the discharge of cleaning fluid through the discharge openings of the blower element in the manner above brought out. Referring then to these figures, the reference character 100 designates a blower element which may be similar in all respects to the blower elements previously described, this blower element being provided with the discharge openings 101 for directing jets of cleaning fluid adjacent the portions of the boiler to be cleaned. A valve strip 102 provided with ports 103 is mounted for longitudinal movement within the blower element by means of the pins 104 and thus resembles the valve strip 26 and the mounting of this valve strip within the blower element.

This form of valve strip differs from that above described in its manner of connection to the actuating rod 105, which rod is similar to the rod 29. For connecting rod 105 to valve strip 102, there is provided a casting 106 welded or otherwise secured to the end of the valve strip. This casting is provided with the depending end flange 107 apertured as at 108 to receive the end of the rod 105, there being provided nuts 109 and 110 for preventing longitudinal movement of the rod through the aperture. A rod 111 is preferably welded or otherwise fixed to the valve strip to reinforce the end of the same adjacent its point of connection to the rod 105, the rod 111 extending from the end of the casting 106 to a point adjacent the first opening formed in the valve strip, as clearly shown in Figure 9 of the drawings.

In place of the valve strips above described, a valve strip such as disclosed in Figures 11 and 12 may be provided for controlling the flow of cleaning fluid through the discharge openings of the blower elements. Referring then to these figures of the drawings, the numeral 115 designates a blower element which may be similar in all respects to any of the blower elements previously described. Threaded or otherwise fixed in the discharge openings 116 of this blower element are nozzles 117, the arrangement being such that each nozzle has a portion 118 which projects within the blower element. These base portions of the nozzles are slotted as at 119 to receive a valve strip 120 which is provided with the spaced ports 121 adapted to register with the passages through the nozzles.

Pins 122 fixed within the blower element to one side of the nozzles form guides for the edge of the valve strip so that the latter is held within

the slots 119, as will be readily apparent. Thus the valve strip will be held adjacent the nozzles by its bearing engagement in the slots in the bases of the nozzles and may be moved longitudinally of the blower element in the same manner as is the valve strip 26 to place the nozzles in communication with the blower element in accordance with a predetermined desired sequence.

10. A still further form which the valve may assume is shown in Figures 13 to 15, inclusive. By reference to these figures it will be noted that there is associated with a blower element 125, which is similar in all respects to the blower elements above described, an internal valve designated generally by the reference character 126. This valve includes a plurality of cylindrical sections 127 which snugly fit within the blower element to close the discharge openings 128 in the blower element. The sections 127 are preferably connected by suitable coupling links 129, these links being fastened to the adjacent ends of the respective sections by pins 130.

15. The arrangement is such that the sections 127 are spaced slightly from each other to provide openings 131 through which cleaning fluid may pass to the openings 128 whenever registration is effected between one of the openings 131 and one of the openings 128. By connecting the sections 127 in the manner illustrated, a slight movement will be permitted between the respective sections so that the entire valve will be somewhat flexible and will not bind upon distortion of the blower element incident to the use 20 of the latter. Thus the couplings between the sections provide for misalignment of the sections so that the valve may follow the movement of the blower element in the event that the latter is deformed at any point throughout its length.

25. 40. At its end the valve 126 is provided with the link 132 adapted for connection with an actuating rod 133 which is similar to the actuating rod 29. The arrangement is such that the valve 126 may be moved longitudinally of the blower element to register the openings 131 of the valve with the discharge openings 128 of the blower element according to a predetermined desired sequence, thus permitting the discharge of cleaning fluid from the blower element at successive 30 spaced points throughout the length of the blower element.

35. From the above it is believed that the invention will be clearly apparent. The various modifications disclosed provide for controlling the discharge of cleaning fluid through the discharge openings of the blower element according to a predetermined desired sequence. Thus a single powerful jet of cleaning fluid may be discharged from the blower element at any one of a plurality 40 of spaced points, and the valve which controls this discharge may be actuated from a point exteriorly of the boiler. The invention further provides for the utilization of different types of discharge nozzles and for the shielding of these 45 nozzles from the heat of the boiler when the blower element is not operating to discharge cleaning fluid. In each form of the invention shown, the arrangement may be such that the end discharge opening in the blower element will 50 be left open to permit a circulation of a cooling fluid through the element, thus preventing destruction of the element by the heat of the furnace.

55. For the sake of convenience the invention has 70 been described as being incorporated in a device

for cleaning boilers. It will be apparent, however, that the invention may be incorporated in devices for cleaning apparatuses similar to boilers, and it is to be therefore understood that the term "boiler" wherever used in the specification or claims is to be construed as meaning a heat transfer apparatus or fluid heater of any character and that the term "boiler cleaner" is to be construed as meaning a cleaner for any such apparatus.

60. 10. While the invention has been described with considerable detail, it is to be understood that the description is for the purpose of illustration only and is not definitive of the limits of the inventive idea. The right is reserved to make such changes in the details of construction and arrangement of parts as will fall within the purview of the attached claims.

15. 20. What we claim as our invention is:

25. 1. In a boiler cleaner, a blower element having a plurality of discharge openings spaced throughout its length, a valve strip within said blower element for controlling the flow of cleaning fluid through said discharge openings, and pins fixed within said blower element and forming bearings for said valve strip for maintaining the same in position adjacent said discharge openings, each pin engaging opposite edges of said valve strip.

30. 2. In a boiler cleaner, a blower element having a plurality of discharge openings spaced throughout its length, an arcuate shaped valve strip within said blower element for controlling the flow of cleaning fluid through said discharge openings, and pins forming bearings for the edges of said valve strip, each pin being fixed to spaced portions of said blower and spanning the space between said spaced portions.

35. 3. In a boiler cleaner, a blower element having a plurality of discharge openings spaced throughout its length, means for supplying a cooling fluid to one end of said blower element, means for closing all but the one of said discharge openings most remote from the end through which the cooling fluid is supplied to the 40 element to compel said cooling fluid to flow substantially entirely through said blower element prior to its escape therefrom through said open discharge opening and means to prevent the escape of the cooling fluid from said blower element except by way of said open discharge opening.

40. 4. In a boiler cleaner, a blower element having a plurality of discharge openings spaced throughout its length, a head associated with one end of said blower element, means for supplying a cooling fluid to said head, means for closing all of the discharge openings in said blower element except that opening most remote from said head to compel the cooling fluid supplied to said head to flow substantially entirely through said blower element prior to its escape from the same and means preventing the escape of the cooling fluid from said blower element except by way of said open discharge opening.

45. 5. In a boiler cleaner, a blower element having a plurality of discharge openings spaced throughout its length, a valve strip arranged within said blower element for controlling the flow of cleaning fluid through said discharge openings, a casting fixed to one end of said valve strip, a reinforcing rod bracing said valve strip adjacent said casting, and an actuating rod for said valve strip fixed to said casting.

50. 6. In a boiler cleaner, a blower element hav-

ing a plurality of discharge openings spaced throughout its length, nozzles fixed in said discharge openings with their base portions projecting into the blower element, and a valve strip 5 within said blower element for controlling communication between said blower element and said nozzles, said valve strip having a bearing within slots formed in the bases of said nozzles.

7. In a boiler cleaner, a blower element, nozzles 10 fitted in discharge openings formed in said blower element, said nozzles having base portions projecting into said blower element and each base portion being provided with a laterally opening slot, a valve strip movably mounted in the slots 15 in said base portions, and guides carried by said blower element for maintaining said valve strip in said slots.

8. In a boiler cleaner, a blower element having 20 a plurality of discharge openings spaced throughout its length, and means within said blower element for controlling the discharge of cleaning fluid through said discharge openings, said means including an elongated flexible tubular member engaging the inner periphery of said blower element and having openings adapted for 25 registration with said discharge openings.

9. In a boiler cleaner, a blower element having 30 a plurality of discharge openings spaced throughout its length, and means for controlling the flow of cleaning fluid from within said blower element through said discharge openings, said means including a plurality of tubular members adapted to engage the inner periphery of said blower element, and links flexibly connecting the 35 end of each tubular member to the adjacent end of the next adjacent tubular member, said links maintaining said tubular members in spaced relation to each other.

10. In a boiler cleaner, a rotatable blower element 40 having a plurality of discharge openings spaced throughout its length, a valve strip within said blower element for controlling the discharge of cleaning fluid through said discharge openings to limit the discharge from said blower element to one discharge opening at a time, and means for actuating said valve strip including a 45 rod fixed to said valve strip, a rack rotatably journaled on said rod, and a gear engaging said rack for reciprocating said rod.

11. In a boiler cleaner, a blower element provided with a plurality of discharge openings spaced throughout its length, valve means within 10 said blower element for controlling the flow of cleaning fluid through said discharge openings, a head for supplying cleaning fluid to said blower element, means associated with said head for rotating the blower element, a rod fixed to said valve means and projecting through said head, a rack rotatably journaled on said rod but fixed 15 against longitudinal movement with respect thereto, and means including a pinion supported by said blower head and engageable with said rack for reciprocating said rack to actuate said valve.

12. In a boiler cleaner, a blower element having 20 a plurality of discharge openings spaced throughout its length, nozzles fixed in said discharge openings, and a valve strip for controlling the discharge of cleaning fluid through said nozzles, said valve strip having a bearing within 25 slots formed in the nozzles.

13. In a boiler cleaner, a blower element having 30 a plurality of discharge openings spaced throughout its length, and means for controlling the discharge of cleaning fluid through said openings, said means including a plurality of tubular members adapted to close said openings and links flexibly connecting the end of each tubular member to the adjacent end of the next 35 adjacent tubular member, said links maintaining said tubular members in spaced relation to each other.

14. In a boiler cleaner, a blower element having 40 one end closed and provided with a plurality of discharge openings, means for supplying a cleaning fluid to said blower element for discharge through said openings, means for closing all but the one of said openings adjacent the closed end of the element, and means providing 45 for the flow of a cooling fluid substantially entirely through said blower element past said closed discharge openings and out of said uncovered discharge opening adjacent the closed end of the element during the time cleaning fluid is not being supplied to the blower element.
